UNITED STATES PATENT OFFICE

ALVIN G. SHERMAN, OF DETROIT, MICHIGAN, ASSIGNOR TO THE DETROIT VAPOR STOVE COMPANY, OF DETROIT, MICHIGAN, A CORPORATION OF MICHIGAN

STOVE STRUCTURE

Application filed January 8, 1930. Serial No. 419,408.

This invention relates to stove structure and has to do particularly with the fabrication, construction and assembly of that portion of a stove or range which surrounds the 5 grate structure, namely, the back splash member, the side splash member, the means for supporting the grates, the drip pan and the warming chamber or cutlery drawer.

Heretofore, in the construction of gas and 10 vapor stoves, the general trend has been towards completely enameled stoves, and designs and constructions which make for cleanliness and sanitation. However, in present construction, the so-called top of the 15 stove or frame which supports the grate structure is usually made of cast iron, and is usually so formed as to present joints that will soon fill up with grease and dirt and make it practically impossible to clean the 20 stove.

It is the object of the present invention to provide a novel form of back splash and front member for the stove top in combination with a novel grate structure, whereby a 25 space will be provided between the grate structure and the stove parts which extends substantially around the grate structure, with the result that all cracks and crevices are done away with and making it possible to keep the 30 stove clean and sanitary while the grates are still in position.

A further feature of the present invention has to do with the formation of the back 35 splash member, which is preferably pressed from one piece of sheet metal, and is preferably bulged or pressed out so that the portion of the back splash member directly above the normal grate line extends rearwardly from the usual position of the back splash 40 member. This construction not only helps materially in the fabrication and assembly of the oven in relation to the back splash member, but also presents a very unique design for the exposed part of the back splash member in that it extends rearwardly of the normal line of the back splash member in graceful curves, and furthermore it directly combines with the support of the grates in that 45 portions of the back splash member adjacent to the level of the grates are pressed out to

form relatively small supporting legs, whereby the corners of each grate member are supported, and leaving the space in between entirely free. Furthermore, this pressed out back splash member continues downwardly 55 past the level of the grates and then converges inwardly to a point above and within the contour of the drip pan.

A further feature of the present invention resides in the construction of the side splash 60 member which extends directly downwardly past the edge of the grate member and converges inwardly to a position above the drip pan, from which position it again extends outwardly and co-operates with the side wall 65 of the warming chamber or cutlery drawer to form a track or runway for the drip pan. A still further feature of this side splash member is the manner in which such member is pressed out and fabricated to receive the 70 fuel conduit leading to the oven burners.

Another feature of the present invention resides in the fabrication and arrangement of the side portion of the stove top adjacent the outer edge, and the front structure of the 75 stove top. This side structure is so fabricated that it converges inwardly similar to the side splash member, and also co-operates with the wall of the warming chamber to form the other track for the drip pan. The front 80 end of the side member co-operates with the front part of the stove structure to support the same, the other end of the stove structure being supported by the side splash member or side wall of the oven. This front 85 stove member is not only so fabricated as to support the front end of the grates similarly to the back splash member, but it also extends forwardly to form the front apron of the stove; or, in other words, the front apron of the stove is so formed as to form the front 90 part of the stove top and to support the grates.

Other features of the invention will be obvious from the specification and claims.

In the drawings:

Fig. 1 is a section taken on the line 1—1 of Fig. 3, and showing in particular the formation of the two side members and the posi- 100

tioning of the drip pan in the tracks formed by said side members.

Fig. 2 is a sectional view taken on the line 2—2 of Fig. 1, and showing in particular the 5 preferred fabrication of the back splash member and front member of the stove top.

Fig. 3 is a plan view taken on the line 3—3 of Fig. 1, and illustrating the fabrication and assembly of those parts of the stove which 10 form the stove top and surround the grate structure.

Fig. 4 is a view taken on the line 4—4 of Fig. 1, showing in particular the top shelf construction and the bulged out portion of 15 the back splash member.

Fig. 5 is an enlarged fragmentary view 20 showing the lower part of the back splash member and one of the lugs for supporting the corner of the grate, and the manner of converging the back splash member to terminate at a point above the drip pan.

Fig. 6 is a sectional view taken in the line 6—6 of Fig. 3, and showing the manner of 25 fabricating the side splasher for receiving the fuel conduit for the oven burners.

Fig. 7 is a sectional view taken on the line 7—7 of Fig. 1 and illustrating the manner 30 of assembling the back splash member and the side member of the stove top.

Fig. 8 is an enlarged fragmentary sectional view illustrating the formation of and 35 the manner of connecting the side member of the stove top and the side member of the warming chamber to form a track for the drip pan.

The present invention is peculiarly adapted to that type of stove known as gas or vapor ranges, the standard types of which are provided with suitable oven and broiler casing, 40 a back splash member flush with the back of the oven, a stove top including a frame for supporting the grate, and a separate chamber or housing positioned beneath the drip pan.

The present invention therefore relates to 45 the standard type of gas or vapor range, but has particularly to do with the fabrication of practically all the parts adjacent the stove top. In Fig. 3 I have shown a plan view of a stove top embodying the present invention, and also showing a portion of the oven wall adjacent thereto. This stove top is so different from the standard top construction that it can only be referred to generally as 50 a stove top as really the top is formed by the side and back splash members and the front apron.

The back splash member may be generally 55 designated 1. Its construction is best illustrated in Figs. 2 and 3. Referring to Fig. 3, 60 the sides of the back splash member may be designated 2 and 3. Fig. 3 being a section taken on the line 3—3 of Fig. 1, it will be obvious that the side 3 of the back splash member is of special formation at the point 65 of section, but that the side 3 takes a regular

form as at 4, in Fig. 7, below the shelf support 5.

As best shown in Fig. 2, the top edge or flange of the back splash member may be designated 6, and the extreme bottom flange 7. This back splash member is preferably formed from a single sheet of sheet metal in a single stamping operation, whereby the dished out portion 8 is formed together with the flanges, as above set forth. This dished out portion 8 of course has the outer edges thereof preferably provided with a smooth curve where it joins the side and top flanges.

The forming of the side flange 2 makes it 80 very easy to assemble the back splash member with the back and side walls of the oven, such assembly between the flange 2, the back wall 9 of the oven, and the side wall 10 of the oven, being best shown in Fig. 3.

Due to the pressed out or dished out portion 8 of the back splash member, it will be seen that the back of this splash member extends rearwardly of the back wall 9 of the oven. This extension is approximately of 90 the same depth as the exhaust flue for the stove, whereby the space which is ordinarily wasted when the stove is positioned against the wall is taken up by this dished out portion 8 of the back splash member.

The bottom part of this back splash member 95 1 gradually curves inwardly as shown at 11 in Figs. 2 and 5, whereby such curved in portion 11 terminates at a point 12 above and within the contour defined by the drip pan 13. The inwardly curved portion 11 is 100 then offset, as shown, to form the flange 7 which co-operates with a suitable shell 14 to complete the back wall of the stove. This back splash member is also preferably formed with pressed out lugs 15 and 16 at the corners thereof, and a lug 17 centrally thereof. Such lugs 15, 16 and 17 are preferably formed 105 in the same horizontal plane, so as to form supports for the grates, as will be presently described.

The oven wall 10 or side splash member 115 of the stove is preferably fabricated as a single unit, and also extends inwardly towards its lower end as at 18, whereby to terminate at a point 19 above the drip pan similarly to the point 12 of the back splash member. Such side splash member is also formed with a side flange 20 which co-operates with a shell 21 so as to form a track 22 for supporting and 120 guiding one side of the drip pan 13. A portion of the shell 21, adjacent the flange 20, is so fabricated as to form the inwardly extending shelf 23. A portion of this side splash member 10, adjacent the point where the burner conduit 24 enters the oven, is preferably pressed out so as to form a flat vertical surface 25 for receiving the flanges of the burner manifold conduits. This structure is 125 best shown in Fig. 6.

The opposite side of the stove structure 130

from the oven wall 10 is formed by a sheet metal shell member 26. This shell member is preferably curved inwardly as at 27 to correspond with the curved in portion 18 of 5 the splash member 10, and is also formed to provide a flange 28 which cooperates with the flange and shelf member 29 to form a second track 30 for receiving the other side of the drip pan. The rear portion of the side member 10 26 is so fabricated as to be secured to the flange 4 of the back splash member 1, and the front end of this side member 26 is provided with a down-turned flange 31, whereby it may be secured to the front member or front 15 apron of the stove.

It will thus be seen that the rearwardly bulged out back splash member, the side splash member, and the outer side wall of the stove, all are inwardly curved at the lower 20 ends, whereby to terminate at a point above and within the contour defined by the drip pan, and also to form a track for receiving and supporting the drip pan.

The front of the stove is provided with a 25 combination apron and front member, which may be generally designated 32. This member 32 consists of the flat horizontal top portion 33, and flange 34 which extends downwardly at right angles and then outwardly 30 to form a ledge for receiving the grates. This apron or front member is adapted to extend past the walls 10 and 26 as best shown in Fig. 3 and suitable lugs 35 and 36 are provided at the front of the oven and the front of the 35 side frame, as best shown in Figs. 2 and 3, for receiving and supporting this entire apron unit. Suitable flanges are preferably secured to the under part of the apron and are provided with slots for fitting around the lugs 40 35 and 36, as best shown in Fig. 2.

The top portion 33 of the front member 32 preferably extends forwardly and downwardly around the manifold 37 to form a front shell or apron 38, which partially covers 45 the manifold and valve mechanism of the stove.

The lugs 15, 16 and 17 on the back splash member and the flange 34 on the front member are preferably so designed as to receive 50 a grate structure, such as diagrammatically illustrated at 39, Figs. 1 and 2. The grate structure, as best shown in Fig. 3, is preferably provided with corner projections which 55 cooperate with the lugs on the back splash member and on the front member, whereby to form spaces between said corner projections which extend completely around the grate members. It will thus be seen that the 60 grate members are not only solely supported by the back splash member and front member to make the same easily removable and increase the simplicity of assembly, but that also a relatively large space is provided which 65 extends substantially around the grates to eliminate all grease and dirt collecting crev-

ices, and to permit easy cleaning at the grate level.

It will thus be seen that I have provided a novel stove structure including a back splash member, a side splash member, a combined 70 front member and apron, and a side member, which are so designed, fabricated and arranged as to greatly reduce the number of parts of the stove structure, and to permit easy, quick, and inexpensive assembly. The 75 pressed out back splash member not only greatly adds to the beauty of the stove and permits easy and rigid assembly of the various parts thereto, but this back splash member, by reason of the fact that it takes up the space 80 back of the stove which is ordinarily wasted, permits the use of a deeper grate, in addition to the fact that it permits the formation of spaces between the grate and back splash member, and is so designed as to support the 85 grate structure and in a novel manner to cooperate with the drip pan. The side members of the stove structure are formed in a novel manner to provide tracks for the drip pan, but has nothing whatsoever to do with the 90 supporting or positioning of the grate members. The front part of the stove completes the stove top and assists in completely eliminating the standard stove top frame, in that the front is so fabricated as to form the front 95 95 of the stove, support the grates, and to cover up the manifold and valve structure.

The apron 32 not only covers up a great part of the manifold and valve structure, but being removable simply by lifting the same 100 off of the lugs 35 and 36 this permits accessibility to the manifold and also greatly simplifies the front of the burner casing. A suitable shield 40 may be positioned beneath the flange 34 of the apron member whereby all 105 four sides of the burner casing as formed by the panels 10, 11, 26 and 40 will present smooth, easy accessible surfaces of pleasing appearance. It will furthermore be obvious that by providing a dished-out portion 8 and 110 by positioning the apron 32 completely in front of the stove structure that a much deeper stove unit is provided with the result that the manifolds of the burner members 115 may be made of the required length as required by manufacturing codes, thus making it unnecessary to obtain length by bending the manifold conduits. To give the drip pan unusual strength, the edges are curled over as best shown in Figs. 1 and 2 and these curled 120 over edges greatly assist in giving the drip pan easy slidability. The interior surfaces of the top shelf and the side bracket also conform to the smooth contour of the back splash member, as best shown in Figs. 1 125 and 2.

What I claim is:

1. In a cooking stove, a back splash member fabricated to provide a dished out central portion and a flange or flanges on one or more 130

of its edges, said flange or flanges being secured to other parts of the stove and said dished out portion extending rearwardly of the back of the stove.

5. 2. In a cooking stove, a back splash member fabricated to provide a dished out central portion and a flange or flanges on one or more of its edges, said flange or flanges being secured to other parts of the stove and said

10 dished out portion extending rearwardly of the back of the stove, the lower part of said back splash member being curved inwardly and terminating at a point above the drip pan.

15 3. In a cooking stove, a back splash member fabricated to provide a dished out portion the lower part of said back splash member being curved inwardly and terminating at a point above the drip pan.

20 4. In a cooking stove, a back splash member fabricated to provide a dished out central portion and a flange or flanges on one or more of its edges, said flange or flanges being secured to other parts of the stove, the said dished out portion extending rearwardly of the back of the stove, and said dished out portion of the back splash member being provided with grate supporting members at the corners and at a central point thereof, whereby to support the corners of the grates only.

25 5. In a cooking stove, a back splash member fabricated to provide a dished out portion extending rearwardly of the back of the stove, said dished out portion of the back splash member being provided with grate supporting members at the corners and at a central point thereof, whereby to support the corners of the grates only.

30 40 6. In a cooking stove, a back splash member fabricated to provide a dished out central portion and a flange or flanges on one or more of its edges, said flange or flanges being secured to other parts of the stove and said dished out portion extending rearwardly of the back of the stove, the lower part of said back splash member being curved inwardly and terminating at a point above the drip pan, and said dished out portion of the back splash member being provided with grate supporting members at the corners and at a central point thereof, whereby to support the corners of the grates only.

35 55 7. A cooking stove comprising a back splash member, a side splash member, and a side member forming the top of the stove for completing the burner pit, said three members converging inwardly at their lower ends, and terminating at points above and within the contour of the drip pan, the bottom of said side splash member and side member being fabricated to co-operate with other sheet metal stove members for forming a lower chamber, whereby to form a track for receiving and supporting the drip pan.

8. A cooking stove comprising a back splash member, a side splash member, and a side member forming the top of the stove for completing the burner pit, said three members converging inwardly at their lower ends, and terminating at points above and within the contour of the drip pan.

10 9. A cooking stove comprising a back splash member, a side splash member, a side member forming the top of the stove for completing the burner pit, said three members converging inwardly at their lower ends and terminating at points above and within the contour of the drip pan, the bottom of said splash member and side member being fabricated to co-operate with other sheet metal stove members for forming a lower chamber, whereby to form a track for receiving and supporting the drip pan, a front member, and means on two of said members for supporting 80 85 the grate structure.

90 10. A cooking stove comprising a back splash member, a side splash member, a side member forming the top of the stove for completing the burner pit, said three members converging inwardly at their lower ends and terminating at points above and within the contour of the drip pan, a front member, and means on two of said members for supporting the grate structure.

95 11. A cooking stove, comprising a back splash member, a side splash member, a side member forming the top of the stove for completing the burner pit, said three members converging inwardly at their lower ends, and terminating at points above and within the contour of the drip pan, a front member, and means formed integrally with said back splash member and front member for solely supporting a grate structure.

100 12. A cooking stove, comprising a back splash member, a side splash member, a side member, and a front member all formed separately but secured together to form a stove top, and pressed out lugs formed integrally on two of said members for supporting the grate structure.

110 13. A cooking stove, comprising a stove structure formed in part by a back splash member and a side splash member, said two members converging inwardly at a point below the grate level and terminating at a point above and within the contour of the drip pan, a portion of said inwardly converging portion of the side splash member being pressed out to form a vertical flange for receiving the flanges of the oven burner conduit.

12. 14. A cooking stove, comprising a stove structure formed in part by a side splash member, said member converging inwardly at a point below the grate level and terminating at a point above and within the contour of the drip pan, a portion of said inwardly converging portion of the side splash member being pressed out to form a vertical flange

for receiving the flanges of the oven burner conduit.

15. A cooking stove, comprising a stove pit, grate structure positioned thereabove, said stove pit being formed by side splash members and a back splash member, said back member extending with a smooth surface past the level of the grate, a front member completing the stove pit, and means forming a part of said back member and said front member for supporting the grate, said front member forming an apron for the manifold structure; and a shield positioned adjacent the underneath side of said front member and extending downwardly to close in the front and fourth side of the stove pit.

16. A cooking stove, comprising a stove pit formed by side splash members and a back splash member, a front member serving as the sole support for one end of the grate structure and being integrally formed to provide an apron for the manifold, said back splash member forming the sole support for the other end of the grate structure and extending rearwardly of the normal back of the stove, said front member being removably secured to the front of the stove and being positioned forwardly of the front of the stove whereby to provide a relatively long stove pit.

17. A cooking stove burner box construction, comprising a back splash member, a front member positioned forwardly of the front of the stove, grate supporting means on said two members, and a grate unit having inwardly spaced sides and supported solely by said back splash member and said front member whereby to leave open spaces between the sides of the grate and the burner box walls and extending substantially the entire length of the side walls.

18. A cooking stove, comprising a back wall, side walls, and a front wall all converging inwardly to form a burner box, and tracks formed adjacent the lower ends of said converging walls for receiving and supporting a drip pan.

19. A cooking stove, comprising panels forming a back splash member, a side splash member and a side member forming the top of the stove for completing the burner box, said back splash member and side splash member extending downwardly with a smooth surface past the normal grate level except for small lugs for supporting corners of the grate, the smooth walls of said splash members extending down past the grate level forming a burner box, said side splash member and side member being fabricated at a point adjacent the lower end of the burner box to provide a portion of a groove for receiving a drip pan.

20. A cooking stove burner box construction, comprising grate structure positioned at the top of and removable from the burner box,

a drip pan positioned adjacent the bottom of the burner box, and a back wall and two side walls enclosing a plurality of burners and forming walls of the burner box between the grates and the drip pan, said three walls being of substantially the same size and contour as said drip pan at their top portion and converging inwardly at their lower ends and terminating above and within the contour of the drip pan.

21. A cooking stove burner box construction, comprising grate structure positioned at the top of and removable from the burner box, a drip pan positioned adjacent the bottom of the burner box, and a back wall and two side walls enclosing a plurality of burners and forming walls of the burner box between the grates and the drip pan, said walls being formed independent of the grate structure and said back wall converging inwardly at its lower end and terminating above and within the contour of the drip pan.

22. A cooking stove burner box construction, comprising a stove top, defined in part by removable grate structure positioned at the top of the burner box, a drip pan positioned below the grate structure, and a back and two side walls supported independently of the grate structure and forming walls of the burner box and extending downwardly from the stove top, said walls enclosing a plurality of burners and converging inwardly and terminating above and within the contour of the drip pan.

23. A cooking stove burner box construction, comprising removable grate structure positioned at the top of the burner box, a drip pan spaced below the grate structure, and a back wall and two side walls forming walls of the burner box and enclosing a plurality of burners and extending downwardly from the grate structure, said grate structure being readily removable without disturbing said burner box, said back wall converging inwardly and terminating above and within the contour of the drip pan.

24. A cooking stove burner box construction, comprising grate structure positioned at the top of and readily removable from the burner box, a drip pan positioned adjacent the bottom of the burner box, and a back wall, front wall and two side walls extending downwardly from the grate structure and forming the walls of the burner box for enclosing a plurality of burners, said front, back and side walls converging inwardly and downwardly to points within the contour of the drip pan.

In testimony whereof I have affixed my signature.

ALVIN G. SHERMAN.
